UNITED STATES PATENT OFFICE.

J. WARD CHILDS, OF NEW YORK, N. Y.

ATTACHMENT FOR WASH-STANDS.

SPECIFICATION forming part of Letters Patent No. 364,479, dated June 7, 1887.

Application filed March 18, 1887. Serial No. 231,358. (No model.)

To all whom it may concern:

Be it known that I, J. WARD CHILDS, of the city, county, and State of New York, have invented a new and useful Attachment for Wash-Stands; and I do hereby declare that the following is a full and exact description thereof, reference being had to the accompanying drawings, and to the letters of reference marked thereon, making a part of this specification.

10 My invention relates to an attachment for wash-stands, and has for its object to facilitate the withdrawal of the slop jar from the lower part of the stand when it is desired to empty the basin therein. This object is attained by 15 the combination, with the lower part of the wash-stand and with a supporting board or tray for the jar so hinged or pivoted as to allow one end thereof to swing out horizontally part way through the opening in front of the stand 20 when the door is opened, of friction-rollers fitted under the board and a spring fitted to bear against its inner end, so as to force the board out automatically when the door is opened, the closing of the door operating to push the 25 board back within the stand, and thereby compress the spring.

In the accompanying drawings, Figure 1 is 30 a view in perspective of a wash-stand with my invention applied thereto. Fig. 2 is a central vertical section taken transversely through the lower part of the wash stand, with the door closed and the jar-board swung in; Fig. 3, a plan view, partly broken away, illustrating an auxiliary device for coupling the jar-board to 35 the door; and Fig. 4, a central vertical section at a right angle to the door at its outer end, illustrating a modification of the invention.

40 A represents a wash-stand, which may be of any approved form, having a lower compartment, B, therein devoted to the reception of a slop-jar, C, and closed by a swinging door, D, in the customary manner.

45 My invention is applicable as an attachment to wash-stands already constructed and now in use, as it may be fitted thereto without requiring any material change or modification in the construction thereof. It consists of a movable horizontal jar board or tray, E, adapted to fit easily into the bottom of the compartment B. The inner end of the jar-board

proximate to the hinges of the door is pivoted centrally to the side of the compartment, the hinged connection being formed by means of an eye and staple, F, or other simple pivotal device, so that the outer end of the board will 55 be free to swing in and out of the compartment through the doorway. This outward movement of the jar-board is produced automatically by means of a spring, K, inserted between the inner rear end of the jar-board and the casing 60 of the stand, and is facilitated by means of friction-rollers G G let into the bottom board of the compartment, so that the jar-board may rest and roll thereon. These rollers G G may be spherical in form, or may consist of wheels 65 whose axes are so fixed as to be radial to the pivotal center or hinge F of the board.

The board may be arrested, when its front end has been carried fully out from the stand, by means of a stop-pin, as at H, Fig. 1, so located as to prevent the board from being drawn out far enough to permit it or the jar resting thereon to tip it over.

The board and jar will be readily forced back into the stand by the closing of the door.

To obtain and facilitate the outward movement of the board and jar, a spring K is inserted between the inner rear end of the jar-board and the casing of the stand. The spring K, being compressed when the board is forced 80 inward, will by its resiliency operate to push it outward as the door is opened.

A chain, J, or, as an equivalent, a hinged link, M, may be interposed between the door and board, so as to admit of ready detachment 85 therefrom to serve, when desired, as an auxiliary to the spring K in producing an outward movement of the board.

In the use of my invention, when the door is opened, the board E, carrying the jar, is 90 forced out by the spring far enough to bring the jar into proper position for convenient use. By closing the door the movable board is forced in again, carrying the jar with it.

As an equivalent for the spring K, or as an auxiliary device, I contemplate mounting the board upon rollers G' G', so arranged (as illustrated in Fig. 4) in the bottom of the stand as to give to the outer free end of the hinged board an inclination to the front, whereby when the 100

door D is opened the board will automatically, by reason of its gravity, swing outward. The friction-rollers G and G', fitted under the board, permit it to move freely and noiselessly, 5 as required.

I do not claim as new a swinging shelf coupled to the door of a compartment so as to be drawn out of the compartment by the door as it is opened and be forced in by the closing 10 of the door, as such a device is well known in connection with the shelves and doors of stove-ovens.

I claim as my invention—

The combination, in a wash-stand, with a 15 door closing a compartment in the bottom

thereof and with a movable board hinged in said compartment to swing out horizontally therefrom, of a spring fitted to bear against the inner rear end of the movable board to force it out toward the door, and friction-rollers 20 fitted under the board to facilitate its movement, substantially in the manner and for the purpose herein set forth.

In testimony whereof I have signed my name to this specification in the presence of two sub- 25 scribing witnesses.

J. WARD CHILDS.
